UNITED STATES PATENT OFFICE.

GEORGE HENRY SCHMUNK, OF CRANBERRY TOWNSHIP, BUTLER COUNTY, PENNSYLVANIA, ASSIGNOR TO PITTSBURGH STOGIE & CIGAR COMPANY, OF PITTSBURGH, PENNSYLVANIA, A CORPORATION OF PENNSYLVANIA.

CONTAINER FOR STOGIES.

1,112,328.

Specification of Letters Patent. Patented Sept. 29, 1914.

Application filed April 29, 1912. Serial No. 693,925.

To all whom it may concern:

Be it known that I, GEORGE HENRY SCHMUNK, a citizen of the United States, and residing in the township of Cranberry, 5 in the county of Butler and State of Pennsylvania, have invented or discovered new and useful Improvements in Containers for Stogies, of which the following is a specification.

10 My invention consists in a new and improved container or package for stogies. My object is to provide a drum or other container wherein the stogies will be protected from longitudinal crushing when 15 the cover is on the container and in which the stogies will be attractively displayed when on sale. The cover or lid of my container is so arranged that it is held away from the stogies in the container to avoid 20 crushing or breaking the same, and when removed may be used for a base in which the bottom of the container may be inserted or stepped to form a firm bearing for the box and to enable the two parts of the 25 severed revenue stamp to be plainly displayed as required by law. A tube or other foreign object of sufficient length to substantially span the distance between the bottom of the container and the cover, when the latter is in 30 place, is packed with the stogies thus supporting the cover against crushing down upon the stogies as frequently happens in the ordinary container.

My new and improved container is provided with a cover which has an internal circumferential shoulder of the same diameter as the body of the container, the cover proper being of sufficient diameter to slip down over the body of the container. The 40 shoulder supports the cover on the top of the body of the container out of contact with the stogies, the cover being also maintained against caving in by the tube as explained above. The body of the container may thus 45 be made short enough to display the upper ends of the stogies to view when the cover is removed, thus attracting purchasers to the wares. When the cover is removed from the top of the container, it may be reversed and 50 the bottom of the container inserted or stepped therein, thus giving the container a firm foundation for the display and sale of goods and at the same time exhibiting in

plain view both portions of the severed revenue stamp as required by law. The usual 55 practice is now to make the cover of larger diameter than the body of the container so that the former slips down on the same and rests upon its contents. Or the diameter of the upper portion of the container is reduced to form an exterior shoulder on the body of the container down against which the edge of the cover rests. In such case the bottom of the box cannot be inserted in the reversed cover to display the goods but is 60 partially inserted therein, so that the container stands unsteadily on an incline, giving an unsightly appearance and often causing the container to be knocked over and the contents spilled on the dirty floor. Frequently the cover is thrown away, thus causing 65 collision with the revenue officers.

In the accompanying drawings, Figure 1 is a vertical section showing my improved container with the cover in place and stogies 75 packed therein, the cover being shown in dotted lines reversed and the foot of the container inserted or stepped therein; Fig. 2 is a similar view of the empty container, the cover being raised slightly for the sake of 80 clearness, and Fig. 3 is a side elevation of a bunch of stogies formed and ready to be inserted lengthwise into the container.

The following is a detailed description of the drawings.

1 is the container which is illustrated as a cylindrical drum but which may be of any cross-sectional shape, such as polyhedral, and preferably formed of cardboard. The body of the container is cheaply made as it 90 is provided with no shoulders or lips but has a plain open top.

2 is the cover provided with a depending edge flange 3 of sufficient capacity to slip down over the upper portion of the body 1. 95 4 is an internal shoulder in said flange 3 formed by fixing a strip of cardboard 5 in the interior of the cover 2, said shoulder being of the proper diameter to rest upon the top edge of the body 1 and to limit the 100 downward movement of the cover 2. This enables me to reduce the height of the body 1 so that the stogies packed therein will extend up above the top edge of the same for the attractive display of the latter, 105 it being characteristic of the stogie-smoker

that he will go first to the box in which the stogies are most prominently displayed to view.

As shown in dotted lines in Fig. 1, the 5 cover 2, when removed from the top of the body 1, is reversed and the bottom of the said body stepped therein, resting upon the shoulder 4, thus giving the container a firm 10 foundation for the display and sale of goods and exhibiting in plain view both portions of the severed revenue stamp, as required by law. The cover is thus put to a useful purpose after the box is opened and is not thrown away to the later embarrassment of 15 the dealer when the revenue inspector calls on his rounds.

My process of packing the stogies in the container is illustrated in Figs. 3 and 1. A strip of paper, cloth or other material, 6, is 20 used to roll the stogies into a compact bunch as shown in Fig. 3, a foreign object or objects, as the paper tube 7, being included in the bunch. Such object is provided with a smooth lateral surface to permit its being 25 drawn from the bunch of stogies to loosen the same without rupturing or tearing their wrappers. When the bunch of stogies is compressed by rolling or manipulation into the proper compass, it is slipped lengthwise 30 into the container 1, being allowed to expand slightly to snugly fit the interior of

said container, the paper 6 being preferably left about the stogies. The tube or other foreign body 7 is preferably somewhat longer than the stogies and when resting 35 upon the bottom of the container extends upwardly to a degree sufficient to come into light contact with the cover 2 when the latter is placed upon the container, thus assisting the shoulder 4 in keeping the cover out 40 of contact with the stogies.

What I desire to claim is:—

A container for the vertical packing of stogies consisting of a body having a constant diameter and a cover provided with a 45 depending flange of sufficient capacity to receive either the top or the bottom of the said body, said flange being provided with an internal shoulder to limit the insertion of the top or bottom of said body therein, and 50 a loose support adapted to be held in place by the stogies and to extend from the bottom of said container to the cover thereof to prevent longitudinal crushing of said stogies, substantially as and for the purpose described.

Signed at Pittsburgh, Penna., this 25th day of April 1912.

GEORGE HENRY SCHMUNK.
